UNITED STATES PATENT OFFICE.

WILLIAM R. BOISVERT, OF ST. DAVID, QUEBEC, CANADA.

DESIGN FOR A PORTABLE LAMP.

57,885.

Specification for Design.

Patented May 17, 1921.

Application filed January 22, 1920. Serial No. 353,836. Term of patent 3½ years.

To all whom it may concern:

Be it known that I, WILLIAM R. BOISVERT, a subject of the King of Great Britain, residing at St. David, in the Province of Quebec, Canada, have invented a new, original, and ornamental Design for Portable Lamps, of which the following is a specification, reference being had to the accompanying drawing, forming part thereof.

The figure is a perspective view of the portable lamp showing my new design.

I claim:

The ornamental design for a portable lamp, as shown.

WILLIAM R. BOISVERT.
